UNITED STATES PATENT OFFICE.

EDGAR ROUSE SUTCLIFFE, OF LEIGH, ENGLAND.

PRESS FOR THE PRODUCTION OF BRICKS, BRIQUETTES, BLOCKS, AND THE LIKE.

Application filed June 23, 1924. Serial No. 721,818.

To all whom it may concern:

Be it known that I, EDGAR ROUSE SUTCLIFFE, a subject of the King of Great Britain and Ireland, residing at 93 Church Street, Leigh, Lancashire, have invented certain new and useful Improvements Relating to Presses for the Production of Bricks, Briquettes, Blocks, and the like, of which the following is a specification.

10 This invention relates to presses of the mould and plunger type for the production of bricks, briquettes, blocks and like consolidated masses from coal or like carbonaceous substances, concrete, clay or other substances or mixtures capable of being consolidated by pressure.

The invention has among its objects to provide a press in which the consolidation of the charges and the ejection of the consolidated masses may be carried out in a simple and effective manner, and to provide a press which is more especially suitable for treating the substances to be consolidated in wet condition.

25 According to the invention there is provided a press for the production of briquettes or consolidated masses of substances capable of being consolidated under pressure, wherein a single mechanism effects the compression of the charge of the material to be consolidated in two or more stages within a stationary mould and the ejection of the consolidated mass from the mould is effected by the stroke of the plunger being extended beyond that necessary for the compression of a charge.

According to the invention, moreover, the stroke of the plunger for effecting the compression of the charge of material to be consolidated is advantageously effected through a toggle mechanism, the reaction upon which is resisted by means operating under fluid pressure.

40 According to the invention, moreover, the walls of the mould are advantageously provided in such manner that liquid contained in the charge to be consolidated may be expressed therefrom either before or during the operation of compression by the action of the plunger.

According to the invention, moreover, the plunger effecting compression is advan-

tageously adapted to reciprocate within the mould through a distance corresponding to the width of several of the consolidated masses, the inner limit of travel being, for example, at a distance equal to the width of three of the masses from the discharge end of the mould, so that three of the masses always remain within the mould during the operation of the press, and a movable cross-head or auxiliary plunger, serving as a mould closure member, is adapted to close the discharge outlet of the mould during the compression stroke of the plunger and while the charge of material freshly introduced into the mould is consolidated and then to withdraw while the plunger performs the extension of the stroke whereby the consolidated mass immediately adjacent the discharge outlet of the mould is forced outwardly for removal by a guillotine or other device.

According to the invention, moreover, the extension of the stroke of the plunger may be effected either by the mechanism effecting the compression stroke or by mechanism specially provided for the purpose, while the withdrawal of the mould closure member may be effected by the plunger mechanism or by a distinct mechanism, the movements of the plunger and of the mould closure member being so determined that the pressure upon the consolidated masses within the mould during the operation of ejection is removed or reduced.

According to the invention, moreover, the pressure exerted by the plunger or plungers upon the material to be consolidated is advantageously maintained uniform by means of a hydraulic plunger and cylinder device connected with the plunger operating mechanism and communicating with an accumulator in which the liquid is maintained under a determined head or pressure.

According to the invention, moreover, the movable mould closure member or auxiliary plunger may be mounted to operate in a cross-head connected by bolts of ample cross sectional area with a second cross-head which conveniently carries the cylinder of the hydraulic cylinder and plunger device before referred to. The compressing plunger may be mounted in a fixed bearing and

may be operated by one element of a toggle mechanism, the other element of which is connected with the plunger of the hydraulic cylinder and plunger device.

- 5 According to the invention, also, the cross-heads before referred to may be supported by pivoted links from, or be slidably mounted upon, the base plate of the press and may be adapted to receive a reciprocatory movement whereby, after the consolidation of the charge within the mould, the discharge may be effected by the movement of the cross-heads and the consequent movement of the plungers in relation to the mould chamber.
- 10 15 The reciprocation of the cross-heads and the bolts may conveniently be effected by means of an operating arm or lever actuated by a cam forming a part of the operating mechanism of the press or actuated by independent mechanism.

According to the invention, moreover, in the use of a hydraulic pressure control device, means are advantageously provided to ensure that when the pressure applied upon 25 the plunger or plungers ceases, the operating mechanism may not be immediately subjected to the full pressure exerted by the accumulator.

30 The mould may be of any suitable construction. It may, for example, comprise a chamber of cross section corresponding to that of the blocks or consolidated masses to be produced and of a length sufficient to permit of the reciprocation therein, according to the cycle of operations, of a compressing plunger of corresponding cross section and to provide space for one or more of the blocks or consolidated masses to be produced.

40 45 Means are provided adjacent the end at which the compressing plunger reciprocates for the feeding of the charges of the substance to be consolidated, and for this purpose, the mould being horizontally disposed, a feed hopper or chamber may be provided above the mould and be fitted with a feed screw or other device for effecting a downward feed of the substance with pressure into the mould.

50 55 The walls of the mould are advantageously formed of series of longitudinal or transverse bars disposed side by side with their lateral faces in contact at least over a portion of the surface lying immediately adjacent the inner face of the mould bars, the contacting surfaces being ground. By such means under the pressure exerted upon the charge the contained liquid is expressed between the bars forming the mould without 60 escape of the substance of the charge. Any other construction of the mould permitting liquid to be expressed may be used. Thus, the walls of the mould may be perforated or slotted, and be formed, for example, by 65 perforated or slotted lining plates suitably

supported against the pressures exerted upon the charges by backing plates or members. The walls of the mould may be formed in the manner described throughout the length of the mould or for a portion of the 70 length only. It will be understood that such a construction of the mould is required only in the consolidation of wet substances but may be employed in the case of dry substances.

75 In substitution for the movable cross-head or movable closure member before referred to, a second plunger may be adapted to reciprocate within or at the discharge end of the mould. The said plunger may be provided to be reciprocated either mechanically or under fluid or hydraulic pressure and the bearing or cylinder within which it operates may be conveniently carried by a fixed cross-head. Such plunger may be adapted to be 80 operated independently of the compressing plunger by distinct driving mechanism or the two plungers may be so relatively mounted as to be operated by a single toggle or other mechanism.

85 90 In the provision of a hydraulic plunger and cylinder device for maintaining the pressure uniform, the plunger or the cylinder is connected to the gearing operating the compressing plunger in such manner that on the forward movement of the compressing plunger the mechanism is adapted to apply pressure upon the hydraulic plunger or cylinder and thus to transmit such pressure to the hydraulic accumulator.

95 100 The means provided to protect the mechanism from the accumulator pressure, when the pressure upon the compressing plunger is relaxed, may conveniently comprise a non-return valve disposed in a connection between the hydraulic cylinder and the accumulator and a bypass of small cross sectional area permitting a restricted flow of liquid from the accumulator to the hydraulic cylinder when the non-return valve is closed. 110 Such bypass may be advantageously provided in the non-return valve.

115 120 The material to be briquetted may advantageously be reduced to a uniform condition of extreme fineness in the dry state, or in the wet state where the material may have been ground with water. And with a view to avoid the use of a binder and to secure effective consolidation, the method of consolidation the subject-matter of the prior Patent No. 1,267,711 is employed, that is to say the material to be briquetted is subjected to compression in a completely closed mould space under such conditions that the expansion of the block or consolidated mass is permitted in a direction transverse to the line of application of the pressure applied under the stresses created within the mould as the result of the compression. This may be conveniently done by providing the mould 125 130

to taper outward towards the discharge end thereof as described in the specification of the prior patent aforesaid.

In the accompanying drawings is represented a construction of the press provided according to the invention, by way of example.

Figure 1 is a sectional elevation of one construction of press.

10 Figure 2 is a plan view corresponding to Figure 1.

Figure 3 is a cross section of the mould chamber represented in Figures 1 and 2, to an enlarged scale.

15 Figure 4 is a detail sectional elevation.

In carrying the invention into effect according to the construction of press represented in Figures 1 and 2 of the accompanying drawings, the press consists of a feed

20 hopper and mould with the compressing mechanism at the forward end and the driving and ejecting mechanism at the rear, all supported upon a substantially rectangular and horizontally disposed base plate *a*.

25 Pairs of links *a*¹, *a*² pivoted respectively upon a bracket or brackets *a*³ and lugs formed upon the base plate *a* serve to support the cross-heads *b*, *c* before referred to which are connected by bolts *d* of ample

30 cross sectional area. The mould *e* is mounted in determined position upon the body of the feed hopper *f* which is supported upon the base plate *a*. The mould is advantageously of such a form as to taper outwardly 35 towards the discharge end thereof as described in the specification of the prior patent aforesaid.

The mould comprises a tubular structure of cross section corresponding to that of the blocks or consolidated masses to be formed and of a length corresponding, for example, to not less than the width of four or five of such blocks. Within the feed hopper *f* there is provided in continuation of the

40 mould a corresponding tubular structure of slide-way *f*¹ within which the compressing plunger *g* may reciprocate and into which the substance to be consolidated may be delivered from the feed hopper *f*, which may

45 be provided with a feed device such as a rotatable screw, or vane mechanism serving to feed the substance into the mould under pressure. The walls of the mould and of the slide-way *f*¹, if desirable, are constructed

50 in such manner as to permit the liquid contained in the charge to be consolidated to be discharged under the action of the compressing plunger. In the construction represented in Figure 3 of the drawings, the

55 mould is formed of a series of bars *e*¹ of suitable cross section disposed adjacent one another so that their lateral faces *e*² are in contact adjacent the inner surface of the mould, the said faces being ground. Towards the outer surface of the mould the

lateral faces *e*² are disposed apart so that channels for the passage of the liquid are provided. A trough *e*³, or alternatively a casing enclosing the sectional or perforated portion of the mould, is fitted to receive the liquid discharged from the mould and to convey it to a waste conduit.

The degree of moisture or content of water in the substance treated may, of course, vary. Thus, in the treatment of 70 coal the charges received into the mould may consist of one part coal to one and a half to two parts of water or may be a mixture containing say 25% of water.

75 The compressing plunger *g* which reciprocates within the slide-way *f*¹ and the mould *e*, is carried upon a slide block *h* disposed within a bearing *h*¹ provided upon the base plate immediately to the rear of the feed hopper *f*.

80 To the rear there are provided upon the base plate two laterally disposed pedestals or standards *i*¹ adapted to carry a horizontally and transversely disposed operating shaft *i* driven by spur gearing or the like. 85

The said shaft is cranked and has connected thereto a connecting rod *i*², to the free end of which is connected a bell crank lever *i*³ or pressure-exerting element of a toggle mechanism connected to the compressing 90

plunger by a pivoted link *i*⁴ and pivotally mounted upon the links *a*² and under the action of a plunger *j* adapted to reciprocate within a hydraulic cylinder *j*¹ mounted or 95

provided in the adjacent cross-head *c*. The plunger is thus adapted to slide into the cylinder when the pressure on the charge exceeds a predetermined value, the cross-head 100

b serving to resist the pressure at the opposite side of the charge. The cylinder *j*¹ is 105 advantageously provided, as in the construction illustrated in Figure 4, with an inwardly projecting portion or rib *j*² at the middle of the length for co-operation with a portion of reduced diameter in the plunger 110

j. The innermost portion of the plunger *j* may be adapted to reciprocate within a lining *j*³ mounted within the rear end of the cylinder and is advantageously fitted with means for forming a fluid tight joint. The 115

cylinder is closed at the rear end by a cover *j*⁴ which also is provided for the formation of a fluid tight joint. A passage is provided through the cylinder cover communicating by way of a swivel joint *j*⁵ with a 120

pipe *j*⁶ which is connected, also by a swivel joint, with a pipe leading to an accumulator in which hydraulic pressure is maintained by means of a pump or the like. In the length of the said pipe or conduit there is provided a non-return valve *j*⁷ permitting the free flow of the liquid to the accumulator. For the return of the liquid into the cylinder there is provided a by-pass passage 125

*j*⁸ of small diameter through the valve. 130

Such bypass may be adapted to be throttled or closed at will by means of a needle valve j^9 fitted within a suitable gland on the casing of the non-return valve.

5 A mould closure member b^1 is disposed co-axially with the compressing plunger upon the cross-head b adjacent to the mould in such manner that it may slide transversely to the axis of the mould to close the mould 10 discharge opening and may co-operate with the compressing plunger in effecting the consolidation of the charges.

For this purpose the mould closure member b^1 is supported by a system of levers 15 and links so connected to the stationary feed hopper and the reciprocating cross-head b that, on the movement of separation of the cross-head from the mould, the closure member b^1 is lifted. The same system of levers 20 and links or a distinct system may serve for the operation of a striker bar and scraper by which the consolidated mass to be ejected may be separated from those in the mould and which is pressed by springs first against 25 the face of the mass projecting from the mould and later against the face of the mould and on the return stroke strikes off the mass and scrapes the face of the mould. The striker bar is conveniently carried upon 30 two arms pivoted upon the pivot pin of the mould closure member and having auxiliary arms or extensions adapted to engage the upper forward edge of the cross-head or cam surfaces provided thereon so as to be 35 maintained in a position to carry the striker bar in front of the projecting mass on the upward movement of the mould closure member. Alternatively, other means may be provided for the removal of the consolidated 40 masses. Thus, in a position immediately adjacent the discharge end of the mould chamber there may be provided a rotatable cutter or guillotine in the form of a star wheel with a series of radiating blades 45 and operated from the press mechanism by suitable gear.

By reason of the manner in which the cross-heads b , c , and the bell crank lever i^3 are supported from the base plate a the ejection 50 of the consolidated masses from the mould is effected by a movement of the said parts in a manner to secure continued forward movement of the compressing plunger g and similar movement of the cross-head b . 55 For this purpose a spur wheel l , mounted loosely upon the shaft i , and driven by a pinion or the like, carries a cam plate l^1 having a cam groove in which engages a roller carried upon an arm or lever l^2 mounted upon a rocking shaft l^3 to which 60 is also secured a pair of arms or levers l^4 . A connecting rod l^5 , of adjustable length, connects the arms or levers l^4 with the cover plate j^4 of the hydraulic cylinder j^1 . The 65 adjustment of the cam plate upon the shaft

i is such as to ensure that the compressing plunger will have completed the stroke imparted to it by the toggle mechanism and will have begun the return movement before the cross-heads and connected parts begin to move. Thus pressure upon the consolidated masses is relieved and the necessary increase in the distance between the mould closure member and the plunger secured that is required to release the mould closure member and permit it to move upwardly without contacting with the adjacent consolidated mass.

The cycle of operations with the press hereinbefore described is as follows:—

Under normal conditions of working there are two consolidated masses in the mould e at the time when the plunger g completes its rearward stroke; during this stroke the mould is opened and a charge of the substance to be consolidated is forced in from the feed hopper f .

During the working or pressure stroke the plunger moves forward, closing the mould and compressing the charge trapped therein so that the liquid contained by it is expressed between the bars e^1 forming the mould.

At the end of the pressure stroke there are three consolidated masses in the mould. During this stroke of the plunger g , the rotation of the cam l^1 has caused no movement of the pressing mechanism, but in the early part of the return stroke of the plunger, the cam causes the forward movement of the cross-heads b and c and the bolts d , so that the plunger g is forced forward and the forward mass is ejected, the other two being moved along the mould, leaving space for a fresh charge.

The movement of the cross-head b lifts the closure or pressure plate b^1 and operates the striker bar and scraper which strikes off the mass and scrapes the face of the mould. By the time the plunger reaches the end of its return stroke, the cam has brought the pressing mechanism back to its normal position for the consolidation of the next charge.

The ejection stroke is the resultant of the combined motions of the crank and toggle links, and the cam, and its extent can be varied if desired by delaying the action of the latter by sliding the driving pinion out of mesh with the wheel l , rotating the latter on the crank shaft, and bringing the pinion into mesh again.

The charge to be consolidated may be prepared under various conditions, for example, by reducing part of the raw material with water to a very finely divided and substantially uniform condition, so that a great portion will pass through a screen of 200 meshes to the linear inch, to produce a slip or slurry, mixing the slip or slurry with the remainder of the raw material in coarser or

granular, but substantially uniform, particles adapted to serve as a water filtering medium distributed throughout the mass and briquetting the wet mass under high pressure in such manner as to filter the greater part of the water therefrom, or by producing an emulsion by grinding pitch to a fine condition in water, mixing the said emulsion with the substance to be briquetted and heating the mixed mass to a temperature not exceeding 212° F and finally compressing the mixed mass for the expulsion of the water and for the production of a solid and coherent block without further treatment.

Means advantageously operated from the driving mechanism may be provided to effect the discharge of the consolidated masses from the moulds of the mould table and the discharge may be effected at a point below the mould chamber. The discharge mechanism may be operated from the main gear or from independent gear.

It will be understood that the invention is not limited to the features of construction hereinbefore described, since this may be obviously varied without departing from the scope of the invention.

I claim:

1. In a briquette press, a stationary mould; means for feeding material to said mould; a plunger adapted to compress said material in said mould; means for moving said plunger to effect said compression; and additional means for moving said plunger, whereby its stroke may be extended beyond that necessary to effect said compression, to discharge said material from said mould, said additional means operating during a portion of the return stroke of said first named means.

2. In a briquette press, a stationary mould; means for feeding material to said mould; a plunger adapted to compress said material in said mould; means for moving said plunger to effect said compression; additional means for moving said plunger, whereby its stroke may be extended beyond that necessary to effect said compression, to discharge said material from said mould, said additional means operating during a portion of the return stroke of said first named means; and a yieldable connection interposed between said additional means and said plunger, whereby the pressure of the latter in said mould may be controlled.

3. In a briquette press, a stationary mould; means for feeding material to said mould; a plunger adapted to compress said material in said mould; means for moving said plunger to effect said compression; additional means for moving said plunger to extend its stroke beyond that obtainable by said first named means, said additional means operating during a portion of the

return stroke of said first named means; and a yieldable fluid pressure connection between said additional means and said plunger, whereby the pressure of the latter in said mould may be controlled.

4. In a briquette press, a stationary mould; means for feeding material to said mould; a plunger adapted to compress said material in said mould; means for moving said plunger to effect said compression; additional means for moving said plunger to extend its stroke beyond that obtainable by said first named means, said additional means operating during a portion of the return stroke of said first named means; a yieldable fluid pressure connection between said additional means and said plunger, whereby the pressure of the latter in said mould may be controlled; and an ejecting member normally closing one end of said mould, said member being operable by movement of said additional means to open said mould and to eject a compressed briquette therefrom.

5. In a briquette press, a stationary mould; means for feeding material to said mould; a plunger adapted to compress said material in said mould; means including a toggle connection for moving said plunger to effect said compression; a bodily movable fluid pressure cylinder; a piston in said cylinder, movable relative thereto; connections between said piston and said toggle connection, whereby the pressure exerted by said plunger in said mould may be controlled by the fluid pressure in said cylinder; and cam means for bodily moving said cylinder whereby the length of the plunger stroke may be extended to eject the compressed material from said mould.

6. In a briquette press, a stationary mould; means for feeding material to said mould; a plunger adapted to compress said material in said mould; a plurality of connected cross-heads movable in the same direction as said plunger; means for moving said plunger; a toggle connection between said moving means, said plunger and one of said cross heads; a bodily movable fluid pressure cylinder; a piston in said cylinder, movable relative thereto; connections between said piston and said cross-head, whereby the pressure exerted by said plunger in said mould may be controlled by the fluid pressure in said cylinder; and cam means for bodily moving said cylinder, whereby the length of the plunger stroke may be extended to eject the compressed material from said mould.

7. In a briquette press, a base, a stationary mould mounted on said base; means for feeding material to said mould; a plunger adapted to compress said material in said mould; a plurality of links pivotally mounted on said base; a plurality of connected

cross-heads, carried by said links and movable in the same direction as said plunger; means for moving said plunger; a toggle connection between said moving means, said plunger and one of said cross heads; a bodily movable fluid pressure cylinder; a piston in said cylinder, movable relative thereto; connections between said piston and said cross head, whereby the pressure exerted by said plunger in said mould may be controlled by the fluid pressure in said cylinder; and cam means for bodily moving said cylinder, whereby the length of the plunger stroke may be extended to eject the compressed material from said mould.

8. In a briquette press, a stationary mould, means for feeding material to said mould; a plunger adapted to compress said material in said mould; a pair of connected cross-heads movable in the same direction as said plunger; a mould closure member carried by one of said cross-heads, means for moving said plunger; a toggle connection between said moving means, said plunger, and the other of said cross-heads, a bodily movable fluid pressure cylinder; a piston in said cylinder; connections between said piston and last mentioned cross-head; and means for bodily moving said cylinder.

EDGAR ROUSE SUTCLIFFE.
